ELASTIC FLUID GENERATOR

Anthony J. Nerad, Schenectady, N. Y., assignor
to General Electric Company, a corporation of
New York

Application June 28, 1939, Serial No. 281,683

10 Claims.

(Cl. 122—235)

The present invention is a continuation in part of my application Serial No. 174,482, filed November 13, 1937, and relates to elastic fluid generators, especially mercury boilers for generating 5 mercury vapor for operating elastic fluid turbines.

The combustion gases which are discharged from the combustion or radiation space of boilers have high temperatures. Therefore to obtain 10 good boiler efficiency, convection zones or spaces must be provided to cool the combustion gases. In order to obtain good heat transfer the tubes or heating elements located within the radiation and convection spaces may be filled entirely with liquid. This, however, would require 15 a prohibiting amount of liquid in the case of mercury boilers because the tubes must be made wide enough to prevent plugging. In mercury boilers the tubes at least in the convection space 20 are ordinarily charged with mixtures of vapor and liquid. In these cases it is important that the inner surfaces of the tubes are wetted by the mercury because a mixture of liquid and vapor has good heat transfer compared to a pure liquid 25 only if the inner surfaces of the tubes are well wetted.

The object of my invention is to provide an improved construction and arrangement of elastic 30 fluid generators, especially mercury boilers having heating elements disposed in radiation and convection spaces or chambers, whereby better efficiency and economy are obtained.

For a consideration of what I believe to be 35 novel and my invention, attention is directed to the following description and the claims appended thereto in connection with the accompanying drawings.

In the drawings, Fig. 1 represents a front view, 40 partly broken away, of a mercury boiler embodying my invention; Fig. 2 is a sectional view along the line 2—2 of Fig. 1; Fig. 3 is a perspective view of certain parts of Figs. 1 and 2, and Fig. 4 illustrates a modification of my invention.

Boilers or elastic fluid generators usually 45 include a drum and heating elements connected to the drum and exposed to heat. The heating elements receive liquid from the drum and discharge a mixture of liquid and vapor into the drum in which the mixture is separated, the 50 vapor being discharged to a superheater or to a consumer and the liquid being recirculated. These boilers are known as natural circulation type boilers. They do not employ any mechanical pumping means for forcing the operating 55 fluid through the heating elements, the flow of

operating fluid through said elements taking place due to the difference in gravity between the operating fluid contained in down tubes not exposed to heat and up tubes exposed to heat. The elimination of pumps, that is, the provision 5 of boilers which may be operated without mechanical pumping means is sometimes desirable when mercury is used as operating fluid, because of the high specific weight of mercury and the consequent difficulties experienced in the pumping 10 of mercury liquid by mechanical pumps. In addition, the use of such pumps requires a great amount of energy which reduces the overall efficiency of the boiler plant. In mercury boilers heretofore built, the mercury was discharged 15 from the up tubes or heating elements into the drum at considerable velocity and at a pressure substantially above the pressure existing within the drum. The high velocity energy contained 20 in the mixture thus discharged into the drum was converted into heat energy within the drum. I have discovered that better use may be made 25 of the available velocity energy of the mixture ordinarily discharged directly from the up tubes of the heating elements into the drum by using this energy to pump fluid, more specifically the same fluid, through another heating element located above the drum and connected in series between the aforementioned up tubes and the drum. In other words, I provide, in accordance with my 30 invention, an arrangement in which the up tubes of the heating elements are considerably extended so that the available energy of the mixture in the portions of the heating elements which are located below the drum is utilized to force 35 such mixture through a tube or tubes located at a level above that of the drum or drums. In such arrangement the mixture is ultimately discharged from the heating elements into the drum at low velocity and at a pressure only slightly above that existing within the drum.

As will become apparent further below, an arrangement in accordance with my invention 45 has many important advantages, for instance, locating certain parts of the heating elements above the drum, that is, in the convection space of the boiler, permits starting of the boiler with said heating elements in the convection space emptied, resulting in a considerable reduction of 50 operating fluid, such as mercury liquid required in the operation of mercury boilers. While my invention is of particular significance in connection with natural circulation boilers, it also applies to forced circulation boilers in which the 55

operating medium, that is the mercury, is forced through heating tubes by means of pumps.

Referring to the arrangement shown in Figs. 1 to 3, the mercury boiler illustrated comprises a plurality of drums or vessels 10, 11 and 12 having end portions projecting through walls 13 and 14 of a furnace. The lower portions of these walls form a combustion or radiation space 15 and the upper portion of the walls forms a convection space 16 receiving combustion gases discharged from the combustion space 15. Connected to the ends of each drum are down tubes 17 and 18 receiving mercury liquid from the corresponding drums. The down tubes are located outside the furnace walls 13 and 14 and their lower ends are branched and connected to heating elements 19, 20, 21 (Fig. 3) located within and lining the furnace walls. The heating element 19 includes three tubes 22, 23 and 24 and the heating element 20 also includes three tubes 25, 26 and 27. Some of these tubes are connected in a well known manner to the bottom of the drum to discharge the mixture of liquid and vapor formed in the tubes directly into the drum, while others of the tubes are connected to heating elements located above the drum. More specifically, the central tubes 23 and 26 of the elements 19 and 20, are connected directly to the bottom of drum 10 whereas the outer tubes 22, 24, 25 and 27 of the elements 19 and 20 are connected to the upper ends of other heating elements or tubes 28, 29, 30 and 31 respectively. These other or second heating elements 28 to 31 in the present instance, are located substantially above the level of the drum 10. The tubes 28 to 31 form a bank or group located within the convection space with the major portion of the tubes arranged transversely to the flow of combustion gases. In the present instance, the tubes have a number or plurality of hairpin shaped substantially horizontally disposed portions forming a zigzag path for the fluid flowing therethrough. The lower ends or outlets of the tubes are connected to the drums.

The heating elements or bank of tubes 28, 29, 30 and 31 have upper ends connected to a source of supply, in the present instance some of the wall tubes in the combustion space, whereas the lower ends of these tubes 28 to 31, inclusive, are connected to the vessel. Thus, the flow through these tubes is in a downward direction wherefore these tubes may be termed downward flow heating tubes and as they are located in the convection space they constitute downward flow convection heating tubes or elements. The downward flow in the downward flow convection tubes facilitates draining of such tubes after shut-down and, what is also important, this downward flow reduces the density of the mixture of liquid and vapor flowing through the tubes during operation. The density is reduced because with the mixture flowing in downward direction the liquid follows the vapor more readily or, from another viewpoint, the slip between the liquid flow and the vapor flow is small as compared with the case of fluid flow in upward direction. Reduced density in the convection tubes permits operation of the boiler with a smaller amount of liquid which is an important consideration in mercury boiler design.

In order to obtain uniform distribution of mercury within the drums, I connect the ends of a group or bank of tubes to different drums. Thus, while such bank of tubes receives mercury from a single drum it discharges mercury into

several drums. From another viewpoint, some of the tubes or heating elements are connected in series between different drums or vessels. This is especially important where the operating fluid consists of mercury and some other substance such as sodium, lithium, aluminum, zirconium, magnesium and titanium, because the connecting of the tubes of one bank to several drums assures the maintenance of uniform concentration of mercury and such substances within the different drums. In the present instance, the tube 28 discharges into a header 32 connected to the drum 10; the tube 29 discharges through a header 33 into the drum 11; the tube 30 discharges through a header 34 into the drum 10, 15 and the tube 31 discharges through a header 35 into the drum 11. The headers 32, 33 are located partly outside the furnace wall 13 whereas the headers 34, 35 are disposed entirely within the furnace. The arrangement is symmetrical 20 as viewed in Fig. 1 and also in Fig. 2. The down tube 18 in Fig. 2 conducts mercury liquid from the drum 10 to a plurality of up tubes 36 and 37. The tubes 36 discharge into the bottom of the drum, whereas the tubes 37 are connected 25 to heating elements or a bank of tubes 38 located above the drum and arranged symmetrically to the aforementioned bank of tubes 28 to 31.

Mercury liquid is conducted to the drums from 30 a source, for instance a condenser (not shown) in the case of a mercury turbine power plant, through a plurality of preheaters. In the present instance a preheater 39 is located between each pair of drums, the preheater 39 has an inlet 35 conduit 40 connected to a U-shaped channel 41; the left-hand leg of the channel 41 is connected to a bank of tubes 43. These tubes 43 are disposed substantially horizontally and partly somewhat below the level of the drums. The outlets 40 of the tubes 43 are connected to a header 44 which in turn is connected through a connecting member 45 to a header 46 located outside the furnace wall and running along the entire boiler to discharge preheated liquid through a plurality of pipes 47 into the different drums. The right-hand leg of the U-shaped channel 41 is connected to another bank of tubes 48 arranged similarly to the bank of tubes 43 and discharging into the same outer header 46.

In order to assure uniform mixture of operating fluid within the different portions of a drum, the several preheaters are preferably arranged so as to discharge into different end portions of the drums. Thus the preheater located between drums 11 and 12 discharges into the end portions of the drums 11 and 12 projecting through the rear furnace wall 14, while the preheater arranged between the drums 10 and 11 discharges through a header 49 into the end portions of the drums 10 and 11 projecting through the front furnace wall 13.

The arrangement shown in Fig. 4 comprises a boiler having a cylindrical wall 60 defining a combustion space 61 and a convection space 62. 65 The lower portion of the wall is reduced in diameter and forms a heating well 63. Burners 64 and 65 are provided in the heating well and the lower portion of the combustion space respectively. A heating element 66 in the form of a helical tube is located in the heating well and arranged to line the wall thereof. Another heating element 67 in the form of a helical tube is located in the combustion space 61 and arranged to line the boiler wall therein. A third heating element 70 75

66 in the form of a plurality of series-connected, hairpin-shaped tubes is located in the convection space 62. The heating element 66 in the well has an inlet portion 69 connected to receive mercury liquid from a liquid vapor separating device 70 located outside the boiler at a level near that of the well. Mercury liquid is forced into the heating element 66 by means of a pump 71 having an inlet connected to the device 70 by a conduit 10 72 and to some other source of supply, (not shown) by a conduit 73. Mercury forced through the heating element 66 in the well is discharged therefrom through a conduit 74 into the upper end of the hairpin-shaped heating elements 68, 15 which latter in turn discharges into the upper end of the heating element 67. The lower end of the heating element 67 is connected by a conduit 75 to the liquid vapor separating device 70. Thus, the three heating elements 66, 67, 68 are 20 connected in series with the drum. The flow through the heating element 66 takes place in upward direction, this element consequently constituting an up-flow heating element, whereas the flow through the heating elements 67, 68 25 takes place in downward direction, said elements consequently constituting downward flow heating elements or tubes.

During operation mercury flows from the drum 10 through the elements 66, 68, 67 in the order 30 stated and is discharged in the form of a mixture of liquid and vapor to the drum 70. The liquid is recirculated through the heating elements, whereas the vapor is discharged from the device 70 through a conduit 76. During starting the 35 downward flow heating elements 67 and 68 are empty of mercury, the lower end of the element 67 and the discharge conduit 75 being located above the mercury liquid level in the device 70. Thus, during starting only the element 66 in the 40 well is filled with mercury. From the element 66 the mercury is forced into the down-flow elements 67, 68 by the action of the pump 71. In case the boiler is operated without the liquid 45 circulating pump 71, mercury is conducted to the downflow heating element only after the liquid contained in the element 66 has expanded sufficiently to fill the conduit 74. The burners or fuel and air supply means 64, 65 may be started simultaneously or consecutively. In case the 50 boiler is operated as a natural circulation pipe boiler, that is, without the pump 71, it may be preferable to start the burner 65 only after the mercury in the heating well has expanded sufficiently to cause flow of mercury through the 55 down-flow heating elements 67, 68. Thus, whereas in the arrangement of Figs. 1 to 3 the down-flow heating elements are located entirely in the convection space, in the arrangement of Fig. 4 said elements are located partly in the convection space and partly in the radiation space.

Summarizing, an elastic fluid generator, in accordance with my invention, includes in addition to a vessel for containing operating fluid and a first heating element located below the level of 65 the vessel and receiving liquid therefrom, another heating element located at a level above that of the vessel and connected in series between the first heating element and the vessel. Operating fluid is conducted to the first heating element 70 through conduits connected to the vessel. The energy of the fluid heated in the first heating element causes this fluid to be forced through the second heating element into the vessel. The first heating element is located at least partly in 75 the combustion space of the boiler while the sec-

ond heating element is located at least partly in the convection space.

An arrangement as that described above in connection with Figs. 1 to 3 in which only a few of the first heating elements are connected to the bottom of the drum or vessel, has the further advantage of reducing the number of openings that have to be made in the bottom of the drum, thus avoiding excessive weakening of the wall of the drum. In a boiler in which the lower or first 10 heating elements line the wall or walls of the combustion space, an increased output of the boiler is effected by connecting at least some of these wall tubes to second heating elements located above the drums or vessels. As the heating elements near and above the level of the vessel may be empty of operating fluid during the starting operation, a considerable economy in operating fluid such as mercury is attained.

As pointed out above, in the case of a mercury 20 boiler the mixture of mercury and vapor is discharged from the heating elements above the drums at a pressure only slightly above that existing within the drums. This naturally means little temperature change of the mercury on its 25 path from said heating elements into the vessels.

It is known that mercury at high temperature 30 dissolves ferrous metal and that this dissolving action is somewhat in proportion to the temperature change of the mercury. Hence, in mercury boilers as described above, owing to the 35 small temperature change of the mercury on its path through the second heating elements into the vessel, there will be little dissolving of ferrous metal by mercury at the operating temperature of the boiler. It is, therefore, safe and proper to use heating elements in the form of tubes. The low dissolving action in a boiler of this kind is especially important in case no substances are added to the mercury to inhibit the 40 dissolving action. The second tubes or heating 45 elements are substantially horizontally arranged in the above described arrangement, that is, transverse to the flow of combustion gases which results in efficient heat absorption of said second heating elements.

Having described the method of operation of my invention, together with the apparatus which I now consider to represent the best embodiments thereof, I desire to have it understood that the 50 apparatus shown is only illustrative and that the invention may be carried out by other means.

What I claim as new and desire to secure by Letters Patent of the United States is:

1. An elastic fluid generator comprising a radiation space, a convection space, a liquid vapor separating vessel, a first heating element receiving liquid from the vessel and being disposed within the radiation space, and a second heating element forming a fluid path of a length substantially greater than the fluid path formed by the first element, the second element being disposed substantially entirely within the convection space and connected in series between the first element and the vessel with the upper end 60 of the second element connected to receive heated fluid from the upper end of the first element.

2. An elastic fluid generator comprising a radiation space, a convection space, a vessel for containing operating fluid, a first heating element 70 located at least partly below the level of the vessel and arranged to receive liquid from the vessel and being exposed to heat from the radiation space, and a second heating element connected in series between the first heating element 75

and the vessel with the upper end of the second element connected to the upper end of the first element, the second heating element being exposed to heat from the convection space and forming a zigzag path for fluid discharged from the first heating element.

3. An elastic fluid generator, including the combination of a vessel for containing operating fluid, a first heating element located below the vessel and having a lower end for receiving liquid from the vessel by gravity, and a second heating element located above the vessel and connected in series between the first heating element and the vessel with the upper end of the second element connected to the upper end of the first element, the length of the second heating element being substantially greater than the length of the first heating element.

4. An elastic fluid generator including the combination of a vessel for containing operating fluid, a first heating element located substantially below the vessel and receiving liquid therefrom by gravity, a second heating element connected between the first heating element and the vessel with the upper end of the second element connected to the discharge end of the first element whereby some of the energy of the fluid in the first heating element is utilized to force the fluid contained in the first element through the second element into the vessel, the second element forming a zigzag fluid path of a length greater than the length of fluid path formed by the first element.

5. An elastic fluid generator including the combination of walls forming a combustion space and a convection space, a vessel between said spaces, a plurality of first heating elements lining the wall of the combustion space, down tubes for conducting operating liquid from the vessel to the lower ends of the first heating elements, second heating elements located in the convection space and having inlets and outlets, said inlets being connected to the upper ends of at least some of the first heating elements and the outlets being connected to the vessel to utilize some of the energy of the fluid in some of the first heating elements to pump such fluid through the second heating elements, the outlets of the other first heating elements being connected directly to the vessel.

6. An elastic fluid generator including the combination of walls forming a combustion space and a convection space, a plurality of vessels for containing operating fluid, first heating elements lining the wall of the combustion space, conduit means for conducting operating liquid from the vessels to the lower ends of the first heating elements, and second heating elements located in the convection space above the vessels and connected

in series between the first heating elements and the vessels, some of the first and second heating elements being connected in series between different vessels to receive operating fluid from one vessel and discharge heated fluid into another vessel to maintain uniform conditions in the various vessels.

7. A mercury boiler including the combination of walls forming a radiation space and a convection space, up-tubes lining the walls of the radiation space, downward flow heating tubes disposed in the convection space, means for conducting mercury liquid by gravity to the lower ends of the up-tubes, conduit means connecting the upper ends of the up-tubes to the upper ends of the downward flow tubes and a vessel located at a level near the lower level of the downward flow tubes for receiving heated mercury therefrom.

8. An elastic fluid generator including the combination of a wall forming a combustion space and a convection space, a liquid vapor separating drum, an up-flow heating element located in the combustion space below the level of the drum and connected to receive liquid from the drum, a down-flow heating element located at least partly in the convection space at a level above the drum and connected in series between the up-flow heating element and the drum.

9. An elastic fluid generator including the combination of a heating chamber, a liquid vapor separating drum, means including a heating element located in the chamber below the level of the drum and connected to receive liquid from the drum for heating such liquid by radiation, a down-flow heating element in the chamber located at least partly above the liquid level in the drum and having an upper end connected to receive heated fluid discharged from the upper end of the first mentioned heating element.

10. An elastic fluid generator including the combination of a cylindrical wall having a lower portion forming a heating well and a combustion space and an upper portion forming a convection space, a liquid vapor separating device located outside the drum at a height to establish a liquid level above the upper end of the heating well, a first heating element located in the well and connected to receive liquid from the drum, a second heating element in the form of a helical coil lining the wall in the combustion space and having a lower end connected to discharge heated fluid to the device, and a third heating element in the form of a plurality of series-connected hairpin-shaped tubes located in the convection space and having a lower end connected to the upper end of the second element and an upper end connected to receive mercury discharged from the first heating element.

ANTHONY J. NERAD.
